US00D562288S

(12) **United States Design Patent** (10) **Patent No.:** **US D562,288 S**
Suk et al. (45) **Date of Patent:** **** Feb. 19, 2008**

(54) **MOBILE PHONE**

(75) Inventors: **Chang-Hoon Suk**, Seoul (KR);
Beom-Ku Han, Seoul (KR);
Chang-Soo Lee, Incheon (KR)

(73) Assignee: **Samsung Electronics Co., Ltd.**,
Suwon-Si (KR)

(**) Term: **14 Years**

(21) Appl. No.: **29/272,151**

(22) Filed: **Feb. 2, 2007**

(30) **Foreign Application Priority Data**

Dec. 1, 2006 (KR) 30-2006-0047763

(51) **LOC (8) Cl.** **14-03**

(52) **U.S. Cl.** **D14/138**

(58) **Field of Classification Search** D14/137,
D14/138, 147, 218, 247-248, 341-347, 496;
455/90.3, 556.1, 556.2, 575.1, 575.3, 575.4;
379/433.01-433.13; 361/814; 348/14.02

See application file for complete search history.
